UNITED STATES PATENT OFFICE.

NEWMAN ESSICK, OF LOS ANGELES, CALIFORNIA.

PLASTER MIXER.

Application filed September 8, 1924. Serial No. 736,466.

This invention relates to a mixer for cementitious material and the like. A popular type of mixer is a portable unit comprising a frame supported upon ground wheels 5 and carrying an engine, a mixer, and gearing connecting the engine and mixer. The present invention is in no way limited to such a unit but is especially useful in such an aggroupment and will be described as 10 embodied therein.

In mixers of the character described, frequent dumping of the batches is required. Where plaster is mixed, frequent washing of the mixing vessel is also necessary. The 15 present invention contemplates a mixer having as a mixing receptacle an open drum, in which a novel rotary impeller or shovel is disposed. The mixer is dumped by turning the drum about the impeller shaft axis. 20 To provide stability during the mixing operation, the drum is arranged to be turned only in one direction, the turning movement in the other direction being limited. The result is that the drum must be turned to 25 dumping position for discharge of the washing liquid. Washing in this manner requires that the mixer be moved away from the batch receiving receptacle or that the latter be moved, in order that the washing 30 liquid may not be discharged therein. The primary object of the present invention is to provide a mixer having a drum which may be turned to one side for dumping the batch, turned to the opposite side for dis- 35 charging the washing liquid, and moving of the mixer or batch receiving vessel is not required. This saves time and labor. An- 40 other object of this invention is to provide a drum so mounted as to be turned without the necessity of gearing or auxiliary power devices. A further object of this invention is the provision of a novel type of impeller 45 efficient both in mixing the batches and in dumping.

These objects together with other objects and corresponding accomplishments are obtained by means of the embodiment of my invention illustrated in the accompanying drawing, in which:

Fig. 1 is a side elevation of a portable mixer unit; Fig. 2 is a side elevation on an enlarged scale as seen looking in the direction of the arrow 2 of Fig. 1, the position of the drum in mixing position being shown in full lines and the position in batch dumping position being indicated by the dotted

lines; Fig. 3 is a side elevation of the drum and its mounting on an enlarged scale, a portion of the drum being shown broken out; Fig. 3^a is a plan view of a fragment of the impeller shown in Fig. 3; Fig. 4 is a fragmentary view in section on an enlarged scale as seen on the line 4-4 of Fig. 3; and Fig. 5 is a view as seen on the line 5-5 of Fig. 4.

Referring more particularly to Fig. 1, a trailer adapted to be attached to a motor car or truck is indicated generally by A. A housing indicated by B encloses the motor and associated means for operating the 70 mixer impeller. The mixer proper is marked C and is shown more in detail in the other figures of the drawing.

The frame of the trailer has mounted thereon bearing standards 6 and 7. Supported by the standards is an impeller shaft 8. Mounted upon the shaft are impeller shovels which stir and trowel the batch. In the present embodiment two shovels are shown. Each shovel comprises a pair of arms 9 se- 75 cured to the shaft and angularly spaced. Connecting a pair of arms are blades 10 ar- ranged so that if extended they would wind about the shaft in a spiral. One shovel winds in the opposite direction to the other. 80 The advancing ends of the shovels are so arranged with respect to the direction of their revolution in mixing that the plastic mass in contact with the blades will slide longitudinally along the same and inwardly 85 of the drum. The blades are turned at their inner ends to form scoops as indicated by 90 11. Secured to the outer ends of the blades are radial scraper blades 12. These blades are arranged to scrape the heads of the 95 drum. The shaft 8 is secured to the engine contained within the housing B so as to be operated thereby.

Pivottally suspended upon the standards by means of bushings 13 which are jour- 100 naled therein, is a drum having a cylindrical shell 14 open at the top. Heads 15 and 16 complete the drum. Secured to the drum is a handle 17 for convenience in turning the drum for dumping. This is the only device 105 provided for turning the drum. Secured to the heads 15 and 16 are angles 18 and 19. The legs of the angles are mounted so as to clear the standards and permit the drum to be turned. Pivottally mounted upon the 110 standards 6 and 7 are lock bars 20 and 21. These bars are arranged so that when their

long arms are turned toward the heads of the drum, the bars will rest against the heads, the lower inner corners of the bars being rounded to permit the latter to be 5 turned into locking position. When the long arms are turned in an upright position, the angle bars 18 and 19 will clear the standards and the lock bars.

Suppose, the lock bars are in locking position as shown in the figures of the drawing, and the impeller is rotating in the direction of the arrow shown in Fig. 2. The drum C will be held against rotation and the batch within the drum will be thoroughly 10 stirred and mixed. After mixing has been performed, and it is desired to dump the batch, handle 17 is grasped, the drum being turned as indicated in dotted lines in Fig. 2 and held against the dragging action 15 of the impeller. The impeller forces the batch from the drum, the scooped ends of the blades holding the plastic mass against slipping inwardly from the blades and the radial blades scraping the mass from the 20 heads of the drum. If it is desired to wash the mixer, the wash liquid is applied while the drum is in the mixing position. To dump the wash water, lock bars 20 and 21 are turned to upright position, thereby permitting 25 the drum to be swung in the opposite direction and to dump the liquid upon the opposite side from the position in which the batches are dumped. During the washing and discharging of the washing liquid, the impeller may be revolved thereby churning and agitating the liquid and thoroughly 30 cleaning the drum.

What I claim is:

1. A mixer comprising a frame having 40 spaced standards, a horizontally disposed shaft journalled between said standards and having mixing blades thereon, a drum sus-

pended so as to be turned about said shaft and having an opening for the introduction and discharge of a charge of material said frame being arranged to permit free lateral discharge of said drum on both sides, abutment members extending from the heads of said drum, and locking members on said standards arranged to be disposed at will 45 in front of said abutment members whereby to hold said drum against rotation in one direction.

2. A mixer comprising a frame having spaced standards, a horizontally disposed 50 shaft journalled between said standards and having mixing blades thereon, a drum suspended so as to be turned about said shaft and having an opening for the introduction and discharge of a charge of material said 55 frame being arranged to permit free lateral discharge of said drum on both sides, abutment angles extending from the heads of said drum, lock means pivotally mounted on said standards so as to be swung into 60 registration with said bars to hold said drum against rotation in one direction with its opening uppermost for mixing.

3. A mixer comprising a frame, a drum 65 rotatably suspended in said frame and having an opening for the introduction and discharge of a charge of material, said frame being clear of obstructions at the side whereby said drum may be turned to discharge at either side thereof, means upon said frame 70 and engaging the end of said drum to permit rotation of the drum in only one direction, said means being movable out of engagement with the drum head to permit the drum to be rotated in either direction. 80

In witness that I claim the foregoing I have hereunto subscribed my name this 18th day of August, 1924.

NEWMAN ESSICK.
